TOBACCO POUCH AND LIKE CONTAINER

Alfred William Flint, London, England

Application March 12, 1936, Serial No. 68,516
In Great Britain March 15, 1935

1 Claim. (Cl. 150—3)

This invention relates to tobacco pouches, handbags, despatch cases and like containers of the kind which consist of a flexible pocket portion formed or provided with a cover flap 5 forming an extension of one wall of the pocket. With pouches and cases of this character the disadvantage has been experienced that the pocket cannot easily be maintained in an open position whilst the contents thereof are in course 10 of removal, and the object of the present invention is to provide an improved construction and arrangement which will obviate this disadvantage.

According to the invention a pouch, handbag, despatch case or like container of the kind above indicated is provided along either or both edges of the pocket portion with a strip of readily deformable non-resilient material of sufficient rigidity to maintain the mouth of the pocket open 20 for any length of time but capable of yielding and returning to normal position as the container as a whole is rolled or folded into its closed position.

Reference will now be made to the accompanying drawing which illustrates by way of example a tobacco pouch constructed according to the invention and in which:—

Fig. 1 is a perspective view with the pocket in the closed position and

Fig. 2 is a perspective view showing the pocket opened.

In the construction illustrated the pouch is made in the known manner from a rectangular strip of leather fabric or other suitable material 35 a one end of which is folded over to form a pocket b by stitching along the edges c the

pocket thus formed being preferably lined with a waterproof material. The edge d of the material which forms the opening of the pocket is folded over and a strip of lead e is fixed within it. With this arrangement when the pouch is unwrapped 5 the mouth of the pocket can be opened by deforming the lead strip e so that the pocket will remain open during such time as the contents are all extracted.

When this operation is finished the edge of the 10 opening is flattened to normal position shown in Fig. 1 and the pouch again folded to its inoperative position in the ordinary manner the strip of lead also serving to maintain the mouth of the pocket closed.

Although the invention has been described above as particularly applicable to the construction of tobacco pouches, it will be obvious that it can be applied equally to other articles such, for example, as handbags and despatch-cases as 20 well as to any leather or fabric containers which require to be held open at certain times.

I claim:

A tobacco pouch comprising a flexible pocket portion defined by opposed walls and having an 25 open mouth, and a cover flap forming an extension of one wall of the pocket portion beyond the mouth thereof and foldable over the pocket portion, and a narrow strip of deformable but non-resilient metal fixed along the edge of the wall 30 of the pocket portion opposite to said extension and adjacent to the mouth of the pocket portion and operative to retain the mouth of the pocket portion in open condition after the same has been opened.

ALFRED WILLIAM FLINT.
